UNITED STATES PATENT OFFICE

1,935,032

BOX MACHINE

Frank M. Joslin, Amsterdam, N. Y., assignor to
Inman Manufacturing Company, Inc., Amster-
dam, N. Y., a corporation of New York

Application June 15, 1932. Serial No. 617,457

19 Claims. (Cl. 93—51)

This invention relates to box making machines of the type shown in my prior Patents 1,356,771 and 1,814,043, and is concerned particularly with certain improvements relating to the plunger 5 employed in such machines.

In machines of this type, the plunger is made up of two relatively movable parts, one part having wings pivotally supported thereon and adapted to be swung so as to bend inwardly the 10 edge portions on two opposite sides of a box blank, the wings being caused to operate by relative movement between the two parts of the plunger. The use of such pivoted wings or folders is generally satisfactory, but in some cases it has 15 been found that such pivoted folders do not operate with entire satisfaction and introduce certain complications into the mechanism.

One object of the present invention is to provide a plunger for use in this type of machine 20 in which pivoted folders are obviated and a simpler and more positive folding construction employed.

A further object is to provide folders which are yieldably mounted on the plunger and normally 25 held in position to contact with the edges of a box in the die and fold such edges inwardly into the path of the descending plunger, the folders themselves being so arranged as to contact with stationary stops to arrest their movement while the 30 plunger continues to move into the die to finish the inward bending of the side flaps on the box.

A still further object of the invention is to provide a plunger built up of parts which can be readily changed to permit variation in the 35 size of the plunger in the manufacture of boxes of different sizes.

Other objects and advantages of the invention will appear to those skilled in the art from the 40 following specification taken with the accompanying drawings forming a part thereof, and in which drawings:

Figure 1 is a side view of a construction embodying my improvements, parts of a die being shown with which the plunger is adapted to 45 cooperate;

Figure 2 is an end view partly in section of the construction shown in Figure 1, certain parts of the plunger being in a different position;

Figure 3 is a fragmentary side view similar to 50 Figure 1, but showing the plunger in a different position;

Figure 4 is a view similar to Figure 3 but showing the position of the plunger after it has entered the die and also showing the position of 55 the folders;

Figure 5 is a horizontal sectional view through the body part of the plunger taken substantially on the line 5—5 of Figure 3;

Figure 6 is a sectional view of the line 6—6 of 60 Figure 3 showing particularly the manner of attaching the bottom plate of the plunger to its supporting bar;

Figure 7 is a transverse section on line 7—7 of Figure 3 showing in detail the friction means 65 for holding the folders in the body part of the plunger;

Figure 8 is a sectional view on the line 8—8 of Figure 1 showing a means for attaching the body part of the plunger to the upper portion thereof;

Figure 9 is a plan view of the plunger and parts 70 of the die on either side thereof; and

Figure 10 is a perspective of the standard to 75 which the body part of the die is secured.

Referring to the drawings in detail by the reference characters thereon, the plunger comprises 80 a main body part which is made up of two side members 10 and end members 11 and 12, all of which are bolted or otherwise rigidly secured together. Also, an end plate 13, preferably hardened, is attached to each end of the body part and suitably secured thereto. A standard 15 is secured to the body part of the plunger, this standard at its lower ends comprising spaced portions or legs 15a. The connection between the legs 15a of the standard and the body part of the 85 plunger is formed as illustrated in Figure 8. Each of the legs 15a on the outside thereof is provided with a slot 15b and a plate 16 is bolted to the top surface of each side member 10 by bolts 16a, the plates 16 engaging the slots in the legs 15a. By this arrangement, it will be understood 90 that the body part of the plunger made up of the members 10, 11, 12 and 13 is capable of slight lateral movement relative to the legs 15a of the standard. One of the legs 15a adjacent its lower end is provided with a stud 17 and a corresponding but shorter stud 18 is secured to the other leg 15a, the latter stud being surrounded by a spring 19 which bears against the adjacent plate 12. The spring 19 will yield and permit lateral 95 movement of the body part of the plunger toward the left in Figure 5 as heretofore described. The stud 17 is arranged to contact with the adjacent member 12 and serve as a stop to limit the lateral movement toward the right of the body part of the plunger relative to the legs 15a of the standard 15. The purpose of such lateral movability of the body part of the plunger will be presently pointed out.

The plunger, as a whole, may be moved toward 110

and from the die, indicated at D, in any suitable manner as by means of a reciprocating cross head indicated at 20 secured to the standard 15 and operated from a part of the box machine.

5 As in the case of the constructions shown in my prior patents, a contact plate 21 is arranged below the body part of the plunger, this contact plate serving to engage the box blanks fed over the die and force the same down into the die 10 before the body part of the plunger comes into operation. The contact plate 21 is secured to the lower end of a rectangular bar 22 which extends upwardly through the body part of the plunger and through the standard 15. The plate 21 is 15 movable toward and from the body part of the plunger and is provided with guides 21a which engage depressions on the outer surfaces of the members 10 of the body part. The bar 22 is frictionally held in the standard 15 by a spring 20 pressed friction member 23 mounted on a plate 24 attached to the upper part of the standard 15. The friction on the bar 22 is so regulated that it will move up and down with the standard 15 but will also yield or slide relative thereto. A 25 spring latch or stop is mounted in the upper end of the plate 24, the same consisting of a bolt or other rounded member 25 mounted in a base 26 on the plate 24 and backed up by a spring 27 held in place by a threaded plug. The bar 22 is provided with upper and lower recesses 28 in which the member 25 may seat when the bar 22 is in one 30 position or the other relative to the standard 15.

In Figure 1 the parts are illustrated in the position they occupy when the plunger starts to move toward the die. When in that position the member 25 rests in the upper depression 28 of the bar 22. After the member 21 enters the die and reaches the bottom thereof and its motion is stopped, the body part of the plunger continues to move downwardly and also enters the die until 40 the parts are in the position shown in Figure 4. When in that position, the member 25 is seated in the lower depression 28 of the bar 22. When the plunger is lifted from the die, the contact plate 21 and bar 22 are carried upwardly by reason of the frictional engagement of the latter with the standard 15 until the upper limit of movement of the plunger is reached. At that time, the bar 22 and contact plate 21 are again 50 forced downwardly into the position shown in Figure 1 by means of a lever 30 pivoted on a support 31 and operated by a link 32 from any suitable part of the box machine as illustrated in my said prior Patent 1,814,043.

55 Referring more particularly to the folders, it will be noted that at each corner of the body part of the plunger I provide posts 33 which are preferably arranged in rectangular recesses in the members 11 and held in position by the plates 60 13. Also guides 34 extend upwardly from the body part of the plunger in which the upper ends of the posts are received. The posts 33 are slidably supported in the body part of the plunger, and to frictionally hold the same relative to the 65 plunger a friction device 35 is arranged to engage each of the posts. One of these devices is shown in detail in Figure 7 and consists of a plunger 36 backed up by a spring 36a. Each of the posts 33 at its lower end is provided with a 70 downwardly and outwardly extending folding portion or foot 37, these portions extending downwardly beyond the lower face of the plunger and laterally beyond the side face of the same. The inner surface 37a of these folding portions is inclined downwardly and outwardly and they con-

stitute the surfaces of the folders which are adapted to contact with the edge portions of a blank in the die and bend such edge portions inwardly into the path of the body part of the plunger as illustrated particularly in Figure 3 in which the upper edges B' of a blank B are shown as engaged by the surfaces 37a of the folders.

80 After the edges B' of the blank have been folded inwardly a sufficient extent to be engaged by the body part of the plunger, it is of course necessary to arrest further movement of the folders into the die. The upper edges of the die blocks D', D² are recessed as illustrated at 40 to receive the folders when the plunger descends. But these recesses 40 are shallow and the bottoms of the same, indicated at 41, act as stops against which the folders 37 engage when the plunger moves downwardly to a certain extent. When the downward movement of the folders is arrested, it is apparent that the same must yield relative to the body part of the plunger in order to permit the latter to move downwardly to the bottom of the die to complete the folding of the blank as illustrated in Figure 4. Such yielding of the folders relative to the body part of the plunger 90 is permitted by the frictional members 35 here- 100 to referred to. In other words, these members yield against the action of the springs 36a and permit the folders to remain stationary while the plunger continues to move into the die. 105

When the plunger is withdrawn from the die it is of course necessary that the folders be returned to their normal operative position in order to be effective on the next downward stroke of the plunger. To accomplish this result a sta- 110 tionary stop 42 is arranged to contact with the upper end of the post 33 of each of said folders as the plunger is withdrawn from the die. The contacts 42 are supported in any suitable manner as by means of a stationary framework 43 115 rigidly mounted on the frame of the machine. The stationary stops 42 are made adjustable as shown particularly in Figure 1 so that they can be set at the proper position to cause the folders to be accurately positioned relative to the lower 120 face of the plunger after the plunger has moved upwardly.

A brief description of the operation of my device will be sufficient. With the parts in the position shown in Figure 1, as the plunger is moved 125 toward the die the contact plate 21 first engages the blank B and forces the same into the die leaving the upper edges thereof in a vertical position. As the plunger continues to move downwardly the folders 37 engage the edges B' of the 130 blank and bend the same inwardly in the path of the body part of the plunger. The yielding connection between the standard 15 and the bar 22 permits the body part of the plunger to continue its downward movement after the contact plate 135 21 reaches the bottom of the die. After the folders have performed their function, they come in contact with the stationary stops 41 formed on the die and the yielding connections 35 between the folders and the body part of the plunger permits the plunger to continue its downward movement and the operation of folding the box is completed. Preferably the side D² of the die is made 140 movable and by suitable mechanism (not shown) is forced against the body part of the plunger to 145 tightly compress the folded parts of the box, and to permit the plunger to yield laterally against such compression the spring 19 is provided. When the plunger is withdrawn from the die, the lever 30 engages the upper end of the bar 22 and 150

pushes the contact plate 21 back to its position below the die as illustrated in Figure 1. Also, as the plunger moves upwardly each of the posts 33 of the folders engages one of the stops 42 which 5 serves to restore each of the folders to its operative position, and the parts are then in condition for another operation.

In devices of this kind it is very desirable to provide for operating on boxes of different sizes. 10 This of course means that the size of the contact plate and of the body part of the plunger must be changed. My arrangement clearly facilitates this result. When it is desired to change from one size of box to another, all that is necessary 15 is to detach the body part of the die from the standard 15 which can be done by merely removing the plates 16 which constitute the only connection between the parts. Likewise, the similar connection between the bar 22 and the contact plate 21 can be removed and a new contact plate and new plunger corresponding to the size of the box desired can be readily substituted.

The invention is of course capable of embodiment in various forms which differ in detail from 25 that heretofore described, and it is to be understood that the invention is not limited to such details except as required by the appended claims.

Having thus described the invention, what is claimed as new and desired to be secured by 30 Letters Patent is:

1. In a machine of the kind described, a die, a plunger movable into and out of the die, a plurality of folders slidably carried by the plunger and normally positioned in advance of the 35 plunger as the same moves toward the die, said folders being arranged to contact with the edges of a blank in the die and bend the same inwardly into the path of the plunger, and means arranged in the path of said folders to contact therewith and arrest their forward movement as the 40 plunger moves into the die.

2. In a machine of the kind described, a die, a plunger movable into and out of the die, folders 45 movable with the plunger as it moves toward the die, yieldable friction means for holding said folders in position to contact with the edge of a box blank in the die and bend the edge of the same inwardly into the path of the plunger, and means on the die to arrest further movement of 50 the folders toward the die after the edges of the blank are bent inwardly.

3. In a machine of the kind described, a die, a plunger movable into and out of the die, folders 55 carried by the plunger and movable therewith toward the die, friction means for holding said folders in operative position to contact with the edges of a box blank in the die and bend the same into the path of the plunger, and means on the die for contacting with and arresting further movement of the folders while the plunger continues to move into the die to complete the folding operation.

4. In a machine of the kind described, a die, a plunger movable into and out of the die, folders 65 carried by the plunger and movable therewith toward the die, said die having parts arranged in the path of said folders to contact with and arrest further movement of the same as the plunger moves into the die.

5. In a machine of the kind described, a die, a plunger movable into and out of the die, folders 70 slidably carried by the plunger, frictional means for holding said folders in operative position to contact with the edges of a box blank in the die and bend the same inwardly into the path

of the plunger, means arranged to contact with and arrest further movement of said folders as the plunger moves into the die, and means for restoring said folders to their operative position when the plunger is moved out of the die. 80

6. In a machine of the kind described, a die, a plunger movable into and out of the die, a plurality of folders slidably carried by the plunger, yieldable friction means for normally holding said folders in operative position as the plunger is moved toward the die, stationary means arranged to contact with and stop the movement of said folders while the plunger moves into the die, and means to restore said folders to operative position when the plunger is moved out of the die. 85

7. In a machine of the kind described, a die, a plunger movable into and out of the die, folders slidably supported on the plunger and movable therewith, friction means for holding the folders in operative position relative to the plunger as the plunger moves toward the die, means to arrest the movement of the folders after the plunger has moved a predetermined distance toward the die, and means to contact with and restore said 90 folders to operative position when the plunger is moved out of the die. 95

8. In a machine of the kind described, a die, a plunger movable into and out of the die, folders carried by the plunger and movable relative 105 thereto, each of said folders having a part normally arranged in front of the plunger to contact with the edge of a box blank in the die and bend the same inwardly into the path of the plunger, stops to limit the movement of the folders toward the die when the plunger moves into the die, and stops to contact with said folders and restore the same to their normal position when the plunger moves out of the die. 110

9. In a machine of the kind described, a die, a plunger movable into and out of the die, folders 115 slidably mounted on the plunger and movable therewith, each of said folders having a part normally positioned to contact with the edge of a box blank in the die and fold the same inwardly beneath the plunger, stops to arrest the movement of said folders when the plunger moves into the die, and adjustable stops to engage said folders and return the same to normal position when the plunger is withdrawn from the die. 120

10. A plunger for box machines having, in combination, means for moving the same toward and from a die, said plunger comprising a body part adapted to enter the die, folders slidably supported on said body part and movable relative thereto, 130 each of said folders having a portion normally extending beyond the front face of said body part and laterally thereof, whereby to contact with the edges of a blank in the die and fold the same beneath said body part as it moves into the die, stationary means arranged to contact with said folders and move the same out of said normal position when the body part of the plunger enters the die, and other means for restoring said folders to said normal position when the plunger is withdrawn from the die. 135

11. A plunger for box machines having, in combination, a body part, a plurality of folders carried by said body part, each of said folders comprising a post frictionally mounted in said body 145 part and each having at its lower end a folding portion projecting downwardly and outwardly and having a surface adapted to contact with and force the edge of a box blank inwardly beneath the body part of the plunger. 150

12. A plunger for box machines having, in combination, a body part, a plurality of posts carried by said body part, each of said posts having a portion rigid therewith at its lower end and positioned to contact with and fold the edge of a box blank inwardly beneath the body part of the plunger, and means for yieldably holding said posts in said body part. 80
13. In a box machine, a die, a plunger movable toward and from the die, said plunger having a plurality of folders mounted thereon and movable relative thereto, friction means engaging each of said folders to yieldably hold the same relative to the plunger, each of said folders having a folding part rigid therewith and provided with a folding surface projecting downwardly and outwardly relative to the plunger, means associated with the die to contact with said folders and arrest the forward movement thereof when the plunger moves into the die, and means to restore said folders to normal position when the plunger moves out of the die. 85
14. In a box machine, a die, a plunger movable toward and from the die, a plurality of posts slidably carried by the plunger, friction means for holding said posts relative to the plunger, each of said posts at its lower end having a folding portion rigid therewith which serves when in normal position to contact with and bend the edges of a box blank beneath the plunger when the plunger moves toward the die, stationary stops associated with the die to arrest forward movement of said folding portions when the plunger enters the die, and stationary means to contact with said posts and move said folding portions into normal folding position when the plunger is moved away from the die. 90
15. In a box machine, a die, a plunger movable toward and from the die, a plurality of folders frictionally carried by the plunger, each of said folders comprising a post having a folding portion rigidly secured thereto, means frictionally engaging each of said posts to yieldably hold said folding portions in normal position to contact with a box blank in the die and fold the edges of the same inwardly, means on the die to contact with said folders and arrest the movement thereof as 95
16. A plunger for box machines having, in combination, a body part having side and end members spaced apart to form an open rectangular construction, a standard extending downwardly in the space between said side and end members, plates detachably mounted on said side member and engaging slots in said standard, whereby said body part is detachably connected to said standard. 100
17. A plunger for box machines having, in combination, a body part, a hollow standard, a contact plate arranged below said body part, a bar extending from said plate upwardly through said body part and said standard, means for detachably connecting said body part to said standard and said contact plate to said bar, whereby body parts and contact plates of different sizes may be readily substituted, and means on said standard for yieldably holding said bar in a plurality of positions. 105
18. A plunger for box machines having, in combination, a body part formed of spaced side and end members, a standard connected to said body part and extending downwardly in the space between said side and end members, a stud mounted in one side of said standard and arranged to engage the adjacent end member, a stud on the opposite side of said standard, a spring surrounding said last named stud and engaging the adjacent end member, said body part being movable laterally relative to said standard against the action of said spring. 110
19. A plunger for box machines having, in combination, a rectangular body part, a post mounted in said body part adjacent each corner thereof, means for frictionally holding said posts relative to the body part, each of said posts at its lower end having a folding portion arranged to contact with and fold the edges of a box blank beneath the body part of the plunger, and means to reciprocate said body part. 115
